SNOWPLOW

Joseph Wandscheer, Sioux Center, Iowa

Application August 5, 1937, Serial No. 157,567

1 Claim. (Cl. 37—43)

My invention relates to a snowplow for highway use principally.

An object of my invention is to provide a snowplow which instead of including spirally arranged elements which cut transversely across a road bed, include a conveying member which bores spirally in the road bed in the direction of travel, and thereby positively drags the snow rearwardly into the mechanism for conveying the snow thus impelled to the sides of the roadway.

A further object of my invention is to provide a fan structure which can be readily reversed for impelling the snow to either side of the plow.

15 A further object of my invention is to provide a cutting member as aforesaid with its shaft directing longitudinally toward the direction of travel and to provide side cutting members which surround the spiral cutting element, which side cutting members extend to the outer forward limit of the forwarding members.

20 A further object of my invention is to provide a spout which can be readily pushed to either side, for throwing snow outwardly to either side of the roadway.

25 A further object of my invention is to provide such side and lower cutting shields which will insure cutting action along the lower surface as well as along the side banks.

30 A further object of my invention is to provide a structure which will instantly break down the snow wall as the plow travels forwardly and divert the same inwardly toward the plow arrangement.

35 A further object of my invention is to provide a structure which will accomplish the above objects with a minimum number of parts and which can be manufactured at a reasonable cost.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a transverse section taken through the plow.

Figure 2 is a view taken substantially along the lines 2—2 of Figure 1.

50 Figure 3 is a detail of a portion of the deflecting spout.

Figure 4 is a forward elevation, and

Figure 5 is a plan view of the plow.

I have used the character 10 to designate generally a truck or other such means for pushing

the plow forwardly. Attached to the vehicle 10 are the braces 11 and 12 which are attached to the vertical channeled member 13 (see Figures 1 and 5). Received within the channels 13 are the sliding angle members 14. A cross bar 15 (see Figures 1 and 5) is attached transversely between the members 14 and pivotally attached thereto at 16 is the rod 17 which is attached to a suitable piston which travels within the hydraulic cylinder 18. Attached to the cylinder 18 is the hose 19 which communicates with the vehicle.

The cylinder 18 is suitably attached to a lower cross bar 20 which is attached between the members 12 and in this manner by forcing oil through the pipe 19 the cylinder will correspondingly permit raising of the plow to any degree necessary. After being set in position the members 13 and 15 can be locked together by suitable bolting arrangements to maintain the plow in fixed elevating position. A cylindrical fan housing 21 is carried by the members 14 and attached within the housing 21 is a further housing 22. The center shaft 23 is journaled within the bearing at 24 and within further bearings 25.

Attached within the inner end of the casing 22 is the larger gear 26 which meshes with a smaller gear 27. The gear 26 is rigidly attached or keyed to the shaft 23 at 28, and the smaller gear 27 is attached to the further shaft 29 at 30. The shaft 29 is attached to a universal joint 31 which is attached to the shaft 32 which is attached to the vehicle powering unit. The universal joint connection permits the power to be applied regardless of the height of the plow unit. The shaft 23 continues into a further square shaft portion 33 which as a variation can be a spline shaft if such is desired. The shaft 33 continues to the shaft 34 which is journaled at 35 and mounted on the shaft 34 at 36 is a sprocket 37. Passing over the sprocket 37 is a chain drive 38 which passes over the further larger sprocket 39 which sprocket 39 is keyed at 40 to the hollow rotating shaft 41. A further gear 42 which is of the same approximate size as the sprocket 37 is free to slide along the square portion 33. A further gear 43 is securely attached at 44 to the hollow shaft 41.

The gear 42 includes projecting teeth 45 which are adapted to mesh with the sprocket 37, and it will be understood that the sprocket 37 is not keyed to the shaft portion 34. The gear 42 includes an inner extension 46 having the channeled portion 47 in which is received the fork 48 which is attached to the rod 49 which communi-

40

45

50

55

cates rearwardly through the casing into the exterior connection 50 which allows the fork to be drawn rearwardly, or conversely.

The hollow shaft 41 rotates on the forward bearing 25 and on a rear bearing 51. Securely attached at 52 to the outer rotatable shaft 41 is the annular member 53 to which the members 54 are attached. Attached to the members 54 are a series of equally spaced vanes or blades 55 of the approximate shape shown in Figure 1. As shown, there are six of such blades although any number can be employed. Attached at 56 toward the forward end of the shaft 23, is a hub member 57. The hub member 57 includes a pair of angularly extending portions 58 to which are attached the spokes 59 and attached to the outer ends of the spokes 59 are the cutting and conveying blades 60.

Attached to the fan housing 21 are the extending side members 61 which gradually diverge therefrom and terminate in the edges 62 which edges are practically flush with the extreme forward edges of the blade 60. The edges 62 extend into the angularly inwardly projecting edges 63 which merge with the bottom 64. The bottom member 64 includes the centrally converging blades 65 which converge to the center as shown more clearly in Figure 5. The bottom 64 slopes upwardly a slight distance and terminates in the casing 21.

The blades 60 include the forward ends 66 which forward ends extend radially a greater distance than the rear of the blades 67. The rear end of the blades 67 are radially a shorter distance than the forward ends 66 and in effect the effective cutting areas described by the blades 60 follow the tapering convergency of the side walls 61 (see Figure 5). Four of such blades can be used or any other number and it will be particularly noted also that the blades surfaces follow a spirally arranged contour starting from the outer ends thereof.

An upper shield can be provided at 68 and a vertical shield at 69 which shield 69 can include an arcuate opening at 70 to permit inward passage of the snow. A spout for deflecting the snow to either side of the plow is provided at the top of the casing 21, the sides of which spout are designated by the character 71. A central shaft 72 is rigidly attached along the surface 73 to the covering flap 74 which is cut away at 75. Rotatably journalled upon the shaft 72 is a further hollow shaft member 76 which is attached along the edge 77 to the further flap 78. The flap 78 is cut away at 79. Attached between the slideable side members 80 on either side of the spout sides 71 are the rods 81. The sides 80 are of the approximate configuration as shown by the dotted structure in Figure 2, and the solid lines in Figure 4.

The shaft member 76 extends through the inner wall 71 into the portion 82 which is attached to the horizontal rod 83. Pivotally attached to the rod 83 is a further rod 84 which in turn is attached to a further horizontal rod 85 which in turn is attached to the shaft 86 (see Figures 1 and 5). The central shaft 72 extends through the portion 82 and is attached at 87 to the further horizontal rod 88 which is attached to the vertical rod 89 which in turn is attached to the further horizontal rod 90 which is attached to the further shaft 91. The shafts 86 and 91 pass to the vehicle. The shafts 86 and 91 are journalled in a suitable bearing member 92 at the termination thereof.

Now that the structure of my device has been explained, I shall proceed to explain the operation thereof.

The plow is forced forwardly by means of the tractor or driving vehicle 10 and during such movement the snow is being cut and conveyed rearwardly by means of the blades 60. In effect the principle involved is that of directly boring into the snow masses so that as the blades 60 enter thereinto, the snow is forced rearwardly through the action of the spiral blades and also through the action effected by the traveling forward of the plow itself. This results in a highly efficient manner of cutting away the snow since a relatively small resistance is encountered in this way. Since the spiral blades 60 follow the general contour of the side blades 62 all of the snow is thereby forced rearwardly without escaping into any side passages, etc. The lower inwardly turned fins 63 naturally assist in this action and the two fins thus concentrate the lower masses of the snow toward the blades. These fins also assist in the slicing action against the snow masses. Meanwhile, the lower blades 65 exert a slicing action against the snow. It should be especially observed that the extension of the side members 61 to the extreme forward ends of the cutting blades present an important feature since they break away the snow from the sides as rapidly as the blades are cutting against the same. In other words, the feature of simultaneously boring into and rearwardly conveying the snow and breaking away the same along the outer edges thereof is achieved by this construction. The snow thus cut is conveyed into the casing 21.

The fan blades 55 then blow the snow upwardly through the spout arrangements. It will be observed that the shaft 23 is driven through the engagement of the gear 26 with the smaller gear 27. In one position of the gearing members the fan will be driven in the same direction through the sprocket drive 38 since such sprocket drive passes over the sprocket 39 and the smaller sprocket 31. This driving arrangement is effected through the arrangement of the gear 42 with the sprocket 37. However, if it is desired to reverse the fan, the rod 49 is pulled inwardly through the connection at 50 which carries the gear 42 along the spline or squared shaft 23 wherein such gear will then mesh with the upper gear 43.

Since the sprocket 37 is rotatably mounted upon the shaft 34, there will then correspondingly be relatively free rotation imparted to the sprocket 41 and the same will ride freely. However, the engagement of the gear 42 with the aforesaid gear 43 will correspondingly result in a reversed motion being imparted to the fan blades due to the natural reversal of gear engagements, which will result in the hollow shaft 41, which carries such blades, being rotated in the opposite direction. The reason for changing the direction of rotation of the fan is to throw the snow to either side of the machine as desired and through the spout arrangement. One side of the spout can be lowered and the other side raised by this construction which is accomplished through the agency of the shafts 86 and 91.

For instance, when the shaft 91 is turned, correspondingly the arm 90 will be pivoted which will carry the link 89 downwardly as well as the horizontal rod 88. This operation will pivot the rod 72 which is attached to the flap 74 and

correspondingly the flap 74 can be raised or lowered, the lower portion of which is shown in Figure 2 wherein the lower edge of the flap rests against the casing 21. Similarly through the agency of the shaft 86 the arm 85 will swing the link 84 in either direction vertically which will pivot the arm 83 which in turn through the hollow member 77 will pivot the flap 78, which flap likewise can be pivoted to the upper limit as shown in the dotted structure in Figure 2 or can be swung downwardly until the lower edge rests against the casing similar to that explained for the flap 74. In this manner the flaps 74 or 78 can be independently pivoted to any height so that the openings left at 92 can be made smaller or larger as desired depending upon the capacity necessary, and also to throw the snow outwardly to correspondingly greater distances.

It will be noted that as the flaps 74 and 78 swing upwardly that they will contact the rods 81 and carry such rods upwardly and at the same time carrying the side members 80 in the same direction. This, then, insures that a complete closure results along the sides of the spouts and also insures that when the flaps 74 and 78 fall to the lowest position, that the members 80 will not thereby be carried downwardly restricting the action of such flaps. The fan blades 55 can be rotated as previously explained to throw the snow according to such direction of rotation, and according to the opening of the spout members. For instance, as shown in Figure 2, the blades are rotated in a counter clock-wise direction since the left hand spout is open.

Another feature provided in my invention is that of cutting away the center masses of snow which are forward of the shaft. To effect this result, I extend the shaft 23 into the extended portion 93. Attached at the extreme end of the portion 93 is the small hub 94. Attached to the hub 94 are a pair of blades 95 which are pitched to a fairly substantial angle. The blades 95 extend outwardly a substantial distance and it will be noted that as the shafts 23 and 93 rotate, the blades 95 will likewise be rotated thereby cutting away the center areas of snow as the machine travels forwardly and in this way an effective cutting surface will be provided radially from the

blades 60 throughout the entire diameter thereof, and in this manner comparatively little resistance will be encountered by the machine. A further bearing 96 can be provided to assist in supporting the further end of the shaft, and brackets 5 97 are attached to the bearing 96 (see Figures 1 and 4) which brackets are attached to the flange 69. It will be understood that other modifications can be made in the plow without departing from the essential principles hereto outlined 10 and it will be understood that the hydraulic lifting arrangement as at 18 can be positioned above the casing 21 if such is desired so that the plow can be lifted upwardly instead of being forced from the lower end. 15

It will now be seen that I have provided a snow plow which will bore directly into snow masses, and thereby convey and force material rearwardly in an efficient manner, that I have provided a fan structure for blowing the rearwardly 20 impelled snow outwardly to either side as desired, that I have provided means for tunneling the snow with side members which tunneling function occurs simultaneously with the aforesaid boring function, that I have provided a snowplow 25 with readily adjustable spout arrangements which can be constricted or expanded as desired independently of each other, and that I have provided a fan structure which can be quickly and conveniently reversed, and that I have pro- 30 vided a plow including the above and further desirable characteristics in a simple construction.

Some changes may be made in the construction and arrangement of the parts of my invention without departing from the real spirit and 35 purpose of my invention, and it is my intention to cover by my claim any modified forms of structure or use of mechanical equivalents, which may be reasonably included within their scope.

I claim as my invention:

A snowplow comprising forward boring and cutting members, a fan positioned rearwardly thereof, said fan including a plurality of radial flaps, said flaps having inwardly recessed portions, a transmission casing received within said recessed portions, a transmission in said casing for driving said boring member and said fan. 45

JOSEPH WANDSCHEER.
